Application April 16, 1928. Serial No. 270,209

21 Claims. (Cl. 175—298)

Our invention relates to electrical switches of the disconnecting type, although, obviously, the invention is not limited to any particular use, but may be employed wherever found suitable.

5 In the preferred embodiment which is herein illustrated, our switch is employed in a power circuit for disconnecting an oil circuit breaker from a normally connected circuit to free the contacts of the oil circuit breaker of potential.

10 Heretofore, it has been the practice to house oil circuit breakers in cells made of suitable insulating material such as asbestos board, cement and the like, with the leads from the busses or lines extending into the cells and into connection with the terminals of the oil circuit breakers. Disconnect switches outside of the cells have generally been provided, preferably in separate cells.

15 Within recent years the practice of employing circuit breakers of the truck type has become accepted practice. The truck type of circuit breakers is movable into and out of its cell on a small truck having rollers, preferably running in a track, so that the oil circuit breaker may be withdrawn from the cell and run out onto the floor for inspection or repair, or the like.

20 Obviously, such removability of the circuit breakers is desirable and, whereas, heretofore, separate disconnecting switches have been necessary in the leads to the oil circuit breakers and releasable connections at the bushing terminals of the oil circuit breakers have been employed, we propose, according to the present invention, to form the connection between the bushing terminal 25 of the oil circuit breaker and the fixed conductors entering the cell through a disconnecting switch, a part of which is carried by the oil circuit breaker bushing terminal and the other parts by the stationary conductor leading into the cell.

25 Obviously, since the travel of the rollers on the floor, or on tracks in the floor, is the only guiding means for governing the alignment of these two cooperating disconnect switch parts, no accuracy of alignment can be relied upon and the switch parts must cooperate within a relatively large tolerance of misalignment.

30 In the preferred form of our invention, we mount a hinge contact member on the oil circuit breaker bushing stud with adjustments to vary the height of the same. We mount the free contact member on an insulating support within the cell and provide a movable blade member hinged on the hinge contact member. The switch 35 arm is adapted to have universal motion at each

of its cooperating contacts, not in the arm itself, but in the connections thereto, since the arm provides the one unalterable dimension. The switch arm and the free contact are provided with means whereby the blade may be locked in closed position.

35 Now, in order to acquaint those skilled in the art with the manner of constructing and operating a device embodying our invention, we shall describe, in connection with the accompanying drawings, a specific structure in which our invention appears.

40 In the drawings,

Fig. 1 is a side elevational view showing the oil circuit breaker disposed in the cell and the disconnectible switch connection between the oil circuit breaker terminals and the stationary terminal mounted on a wall of the cell;

45 Fig. 2 is a side elevational view, on an enlarged scale, showing the switch blade, its lock and the contacts cooperating with the switch blade;

50 Fig. 3 is a front view of the same as though taken from the right of Fig. 2;

55 Fig. 4 is a top plan view of the stationary contact;

60 Fig. 5 is a vertical sectional view through the hinge contact and a part of the blade;

65 Fig. 6 is an endwise view of one of the members of the hinge contact; and

70 Fig. 7 is a face view of the same.

75 Referring now to the drawings, the oil circuit breaker 1 is housed in the cell 2, this cell comprising an elongated, vertical, cubical receptacle having a door at the upper end thereof as indicated at 3, which is mounted on hinges. This door 3 may be swung open when it is desired to wheel the oil circuit breaker 1 out on the rollers 4—4, which preferably have a guiding track in the lower part of the cell 2.

80 It is old to wheel a truck-type oil circuit breaker into a cell and have contacts of the same engage stationary contacts mounted on the wall of the cell, but the difficulty with that construction is, that a separate disconnect switch is necessary or the oil circuit breaker would have to be wheeled out of its cell if mere disconnection were desired.

85 The oil circuit breaker 1 and its operating mechanism, as well as its supporting truck and guiding track, are known in the art and form no novel part of our invention. The guiding track for the rollers is indicated at 5, so that when the truck with the oil circuit breaker thereupon is wheeled into the cell, it will assume, as nearly as possible, a predetermined position.

90 The oil circuit breaker has a pair of bushing 110

studs 6 which are connected down through the insulating bushings 7 to the contacts within the oil chamber 8, the movable contact bridging the same being controlled by suitable operating mechanism 9, which may be of any preferred or desired construction. The studs 6 are spaced apart a suitable distance and extend substantially vertical, one behind the other as viewed in Fig. 1. Each of these studs is threaded, and a suitable split 10 threaded clamp 10, adjustable vertically, is mounted on the corresponding stud 6 and locked in position. The split clamping ears 12-12 are adapted to be drawn together by bolts 13-13 to lock the member 10 upon the stud 6. The 15 body of the clamp 10 has a flat-sided stud 15 formed integrally therewith and extending vertically above the same, as viewed in Figs. 1 and 3. To the sides of the stud 15 there are clamped the contact and terminal pieces 16-17 by means of two through bolts 18. These contact pieces 20 16 and 17 comprise tubular members, such as copper tubing, mechanically stamped or compressed upon the braided copper ribbons 20 and 21, respectively, and upon flat leaf springs 22, 23 and 24, 25, respectively. This shrinking or compressing of the copper tubing upon the ends of the copper ribbons and upon the leaf springs is preferably done in a punch press. The through bolts 18 clamp these terminal members and their 25 connected parts firmly on the stud 15. The cantilever springs 22-23 and 24-25 tend to bow toward each other.

At their upper ends the copper ribbons 20 and 21 are clamped in a similar manner within the plates 26 and 27, which are formed of copper tubing compressed mechanically upon the ribbons 20 and 21.

A blade member 30, which in this case is a bar of hard drawn copper, has its hinge end embraced by the plates 26 and 27 which comprise the hinge contact of the switch. The corners of the lower end of the blade are chamfered off to avoid cutting the contact plates 26 and 27 if the blade 30 is moved while out of alignment. The structure of the plate member 27 is illustrated in Figs. 6 and 7. The plate member 26 is identical with the plate member 27 and a description of one of them will suffice for both. These plate members have a central hole 31 therethrough, the edges of the hole being chamfered off and the hole being larger than the shank of the bolt 32 which extends therethrough.

The edges of the holes 31 and the edges of the hole through the switch blade are countersunk 55 on both sides. In Figs. 6 and 7 the lower ends of the copper ribbons are shown as prepared for assembly in the plates 16 and 17. Obviously, instead of shrinking the copper tubes upon the lower ends and upon the lower ends of the springs, the springs, ribbons and terminal blocks may be assembled merely by bolting.

The plates 26 and 27 have pins or studs fixed thereto, these studs 33 and 34 having collars 35 thereupon, and the opposite ends being riveted 60 into countersunk holes in the plates 26 and 27 so that the studs 33 and 34 are rigid with the plates 26 and 27. The purpose of the studs 33 and 34 is to prevent turning or angular motion of the plates 26 and 27 on the bolt 32. These 65 studs 33 and 34 extend through holes in the upper ends of the springs 23 and 25, which springs extend beyond the ends of the springs 22 and 24, although this feature is optional.

The pivot bolt 32 extends through the springs 75 22-23 and 24-25, drawing them towards each

other. Between the flat springs and the plates 26 and 27 we dispose the spring washers 36 and 37, which are preferably segments of a hollow sphere, or they may be small truncate cones, their function being to spread the pressure of the springs and the tension of the bolt 32 over the plates 26 and 27 to assure a proper distribution of pressure between said plates 26 and 27 and the blade member 30 between them. At the same time, since the holes in the springs 22-23 and 24-25, through which the bolt 32 passes, is made relatively loose so that the bolt 32 has a small degree of angular freedom for lateral swinging motion of the blade 30, the interposition of the spring washers 36 and 37 permits motion of the blade with the plates flat against the same to the desired limited extent without binding.

From the above it will be seen that the blade 30 has its proper pivotal motion on the axis of the bolt 32 for swinging from closed vertical position to open horizontal position, such as is customary in a switch of this type, but, in addition, the blade 30 has a limited play laterally, that is, to the right or to the left, as viewed in Fig. 3, about the lower contact terminal, without adversely affecting the maintenance of satisfactory contact between the blade and its cooperating hinge contacts. Also, due to the fact that the springs on which the bolts 32 are mounted extend upwardly substantially in parallel relation, they 100 permit lateral or bodily displacement sidewise of the lower end of the blade without loss of contact. There is, therefore, free swinging motion of the blade for the normal opening and closing thereof in the plane of the blade, and the plane 110 of the blade may be varied by a limited degree of motion in the hinge connection.

The upper contact member 39, which cooperates with the upper end of the blade 30, has a construction in many ways similar to the lower hinge contact. The upper contact 39 is mounted upon the stud 40 which forms a part of a threaded rod 41 extending through the insulating sleeve 42, which insulating sleeve extends through and is mounted upon the wall or barrier 43 forming the back of the cell 2. The rod 41 is provided with a shoulder 44 which is drawn against one end of the insulator sleeve 42 by means of the nut 45 which is threaded upon the opposite end of said rod 41.

A two-part split clamp embraces the central part of the insulating sleeve 42 and it has ears, such as 47-47 whereby the same may be clamped to the barrier 43.

The outer end of the rod 41 is provided with a 130 pair of clamping nuts 48 whereby the rod may be connected to a bus bar or other suitable conductor.

Connecting plates 59 and 61, which are preferably made of copper tubing mechanically compressed or swaged upon the ends of the copper ribbons 52-53 and the corresponding leaf springs 54 and 55, are bolted to the sides of the stud 40 as by a pair of through bolts 56. The leaf springs 54-55 are multileaf cantilever springs, two of the leaves extending forwardly and being apertured to receive the pins 57 and 58, which are connected to the lock plates 59 and 60 and to the contact plates 61 and 62 which are preferably made of copper tubing swaged upon the corresponding ends of the copper ribbons 52 and 53. These contact plates 61 and 62 are provided with integral divergent horns 63 and 64 for guiding the blade 30 into proper location between them. The innermost leaf of the springs 54 and 55 ex-

tends forwardly and is apertured in each case to receive the corresponding pins 65 and 66, these pins being provided with suitable shoulders 67 and having their inner ends riveted in countersunk holes in the contact plates 61 and 62.

In like manner, the pins 57 and 58 have spherically shaped shoulders 68-68 facing outwardly, and the inner ends of the pins 57-58 extending through the plates 59 and 60 and the corresponding contact plates 61 and 62 being riveted over in countersunk holes therein.

The pins 57-58 and 65-66 are loosely held in the corresponding holes. The shoulders 67 do not extend into contact with the leaf springs 15 as do the spherical shoulders 68, so that a limited universal motion of the contact members 61 and 62 is permitted and, at the same time, these contact plates are pressed towards each other by the cantilever springs 54 and 55. The pins 65-66 prevent rotation of the contact plates 61 and 62 on the axis of the pins 57-58.

The contact plates 61 and 62 can be displaced laterally by flexing of the cantilever springs 54 and 55, these springs being tensioned so as to 25 press the corresponding contact plates towards each other under appreciable tension even when the blade 30 is out from between them.

The locking plates 59 and 60 extend upwardly, as viewed in Fig. 2 to provide locking shoulders or detents 70, back of which the locking bolts 71 may drop to prevent opening movement of the 30 blade 30. One of these plates 60 likewise has an extension 72 overlying the other contact plate back of the position where the rear edge of the 35 blade should come when it is in closed position.

This serves as a limiting stop for the closing movement of the blade 30.

The locking bolts 70 are formed on opposite sides of a slidable sleeve member 73 which is 40 slidable endwise on the end of the blade 30, all as disclosed in the co-pending application of Eric Nordhem, Serial No. 137,833, filed September 27, 1926, to which specific reference is here made for a disclosure of the locking mechanism.

Suffice it to say here that the operating eye member 75 is pivoted on the pin 76 which extends through the upper end of the sleeve 73, this member 75 having a flat cam, as indicated in dotted lines at 77, engaging the outer square end of the blade 30, and a spring urging the sleeve 73 downwardly as viewed in Fig. 2 to force the lugs 71 downwardly back of the shoulders 70. The lugs 71 are made wide enough to reach across the contact plates 61-62 to engage back of the 55 shoulders 70 on the locking plates 59 and 60.

It can be seen that the contact plates 61 and 62 have limited universal motion. The pins 65 and 66 pass through slotted holes in the inner leaf of the spring members so that a limited 60 rotational motion in the plane of the paper in Fig. 4 can occur. Obviously, a rocking motion in the plane of the pins 57-65 and 58-66 is free to occur, and the plates may obviously be displaced laterally or bodily in the plane of the 65 paper as viewed in Fig. 4 by virtue of the mounting on the flat springs 54 and 55.

Due to the fact that the contacts 61 and 62 will follow the blade 30, and due to the fact that the locking sleeve 73 is mounted on the upper 70 end of the blade and, hence, also follows it, it will be apparent that for all positions of the parts when the blade is closed with the contacts 61 and 62, the locking lugs 71 are able to lock effectively back of the shoulders 70.

75 The action of the locking mechanism is auto-

matic in that rocking of the eye member 75 about the pivot 76 withdraws the lugs 71 from back of the shoulders 70 when the eye 75 is pulled to open the switch and, likewise, upon closing the switch the pressure upon the eye member 75 80 raises the locking lugs or bolts 71 until the switch blade engages the stop 72 and upon release of pressure the spring means which urges the sleeve 73 downward, as viewed in Fig. 2, throws the locking lugs 71 back of the shoulders 70.

The operation of the device shown in Fig. 1 is believed to be apparent from the foregoing description. When the oil circuit breaker is to be disconnected only, the operating mechanism is tripped to open the oil switch and thereafter, by the insertion of a switch stick hook in the eye of the member 75, the member 75 is pulled outwardly, releasing the locking lugs 71 from the shoulders 70 and permitting the switch blade 30 to be pulled outwardly. If desired, a grounding bus may be mounted on a part of the frame of the oil circuit breaker 1 so that the switch blade 30 may be swung into contact with such a grounded contact leading through a grounded cable to neutral ground.

If the circuit breaker is to be removed from the cell 2, the operating mechanism is first tripped and, thereafter, the switch blades 30 on each of the terminals of the oil switch are opened and the oil circuit breaker may be wheeled out of 105 the cell where it is available for inspection, repairs and the like.

It is to be understood that the oil circuit breaker 1 has two terminals and, consequently, there are two disconnect switch blades 30 for each of the 110 oil circuit breakers; hence, for a three phase line there are six disconnect switches. Since, however, they are identical in structure and mode of operation, it is not deemed necessary to show them.

Since the details of construction and dimensions of the oil circuit breakers may vary within limits, the adjustable coupling 10 may be raised or lowered to adjust the proper position of the hinge contact with respect to the free contact. 120 The clamp 10 may be turned on the stud 6 so as to alter the normal plane in which the blades 30 swing. The rod 41 through the insulator 42 may be adjusted angularly to align the free contact as nearly as possible with the plane of 125 the blade.

We do not intend to be limited to the details of construction shown or described. We believe that it is broadly new with our invention to provide a separable disconnecting switch on the 130 terminals of an oil circuit breaker, the blade being hinged on either the stationary member or on the movable terminal member of the oil circuit breaker within our invention, although, in our opinion, the construction shown is preferable. We believe, also, that it is broadly new in our invention to provide a switch in which provision is made for limited but definite universal play at both the hinge contact and the free contact.

While we have shown a specific form of lock, it is to be understood that the form of the lock may be varied widely, within limits, so long as the lock parts which are carried by the stationary contact follow the stationary contact in adapting 145 themselves to the alignment of the switch blade and its lock parts. It is therefore broadly new in our invention to permit one of the lock parts to have freedom of adjustment to adapt itself to the other lock parts which, with respect to its 150

support, does not have the freedom of adjustment. In fact, it is broadly new to have any of the lock parts provided with a small degree of universal freedom.

5. We claim:—

1. In combination, a first contact, a stationary insulating support therefor, a second contact, an insulating support therefor, said last mentioned insulating support being movable with respect to the first mentioned support, and a switch arm hinged on one of said contacts and cooperable with the other of said contacts when the movable support is in a predetermined position, said contacts being provided with mountings on their supports permitting a limited degree of freedom of motion with respect to one another.

2. In combination, a cell, a stationary contact mounted in insulated relation on a wall of the cell and being disposed in said cell, a movable truck-type oil circuit breaker normally disposed in the cell and movable out of the same, said circuit breaker having a terminal, a contact permanently mounted thereupon, and a switch arm hinged on said latter contact and cooperable with the stationary contact, the contacts being movably mounted with respect to one another independent of movement of the breaker.

3. In combination, a container forming a cell, a stationary contact mounted in insulated relation in said cell and extending in a horizontal position within the cell, a movable truck-type oil circuit breaker normally disposed in the cell but movable out of the same, said circuit breaker having a vertically disposed terminal, a contact permanently mounted on said terminal, but being adjustable vertically thereupon, and a switch arm hinged on one of said contacts.

4. In combination, a housing forming a cell, a horizontal sleeve of insulation extending through a wall of the cell, a conductor mounted in said sleeve and having a horizontally extending terminal, a truck-type oil circuit breaker normally disposed in the cell, tracks in the cell for guiding the circuit breaker into a predetermined position, said circuit breaker being movable out of the cell on said tracks, said circuit breaker having a vertically extending terminal, a vertically adjustable connector on said terminal, a hinge contact mounted on said connector, and a switch arm mounted on said hinge terminal and adapted to cooperate with said horizontally disposed contact.

5. In combination, a housing forming a cell, a horizontally extending insulator in the upper part of the cell, a terminal mounted on said insulator, a pair of contact jaws flexibly mounted on said terminal, a truck-type oil circuit breaker in the cell, said circuit breaker having a bushing terminal, a pair of jaws flexibly mounted on said bushing terminal, and a switch arm hingedly mounted between one of said pair of jaws and cooperable with the other of said pairs of jaws.

6. In combination, a horizontally disposed insulator having a terminal thereupon, a pair of contact jaws mounted on said terminal by mounting means permitting a limited degree of motion, a truck-type circuit breaker having a bushing terminal, a pair of jaws mounted on said bushing terminal by mounting means permitting a limited degree of motion, and a switch arm hinged between one of said pairs of contact jaws and adapted to cooperate with the other pair of contact jaws.

7. In combination, a horizontally disposed insulator having a terminal member mounted thereupon, a contact member, a mounting for said contact member on said terminal permitting a limited degree of motion of the contact member, a truck-type oil circuit breaker having a bushing terminal, a contact, a mounting for the contact on the bushing terminal permitting a limited degree of motion of the contact with respect to the bushing terminal, and a switch arm hinged on one of the contacts and cooperable with the other of said contacts.

8. In a switch, the combination of an insulating bushing, a conductor mounted in the bushing and having an extension therebeyond providing a flat-sided clamping stud, a pair of clamping plates upon the opposite sides of said stud, each of said clamping plates having a flexible lead extending therefrom and a cantilever spring secured thereto, contact plates connected to the flexible leads and supported between the ends of the cantilever springs, said cantilever springs pressing the contact plates towards each other, a switch blade lying between the contact plates, a hinge bolt passing through the cantilever springs, the contact plates and the switch blade, and convex washers disposed between the cantilever springs and the switch blade.

9. In a switch, a terminal plate comprising a tubular conductor, a cantilever spring and a flexible lead fixedly secured in said tubular conductor, a contact plate comprising a tubular conductor having the flexible leads secured thereto whereby the contact plate is electrically connected to the terminal plate, and a pair of projections on the contact plate extending through the ends of the cantilever spring, one of said projections having a convex shoulder spacing the cantilever spring from the sides of the plate.

10. In combination, a terminal plate, a flexible lead and a cantilever spring anchored to said plate, a contact plate having the flexible lead anchored thereto for providing electrical connection between said plates, said second plate having a loose mechanical connection with the cantilever spring.

11. In combination, a mounting stud, a pair of terminal plates clamped to the stud, a cantilever spring and a flexible lead permanently secured to each of said terminal plates, contact plates secured to said flexible lead and lying between said cantilever springs and pressed towards each other thereby, a switch blade lying between the latter plates and a bolt passing loosely through the spring, the plates and the blade.

12. In combination, a mounting stud, a pair of terminal plates clamped to the stud, a cantilever spring and a flexible lead permanently secured to each of said terminal plates, contact plates secured electrically to the said flexible leads and being disposed between said cantilever springs and pressed towards each other thereby, a switch blade lying between the latter plates, a bolt passing loosely through the springs, the plates and the blade, and outwardly convex spacing means lying between the springs and the outsides of the latter plates.

13. In combination, a mounting stud, a pair of terminal plates clamped to the stud, a cantilever spring and a flexible lead permanently secured to each of said terminal plates, contact plates secured electrically to the said flexible leads and being disposed between said cantilever springs and pressed towards each other thereby, a switch blade lying between the latter plates, a bolt

- passing loosely through the springs, the plates and the blade, and outwardly convex spacing means lying between the springs and the outsides of the latter plates, and pins secured to said 5 latter plates and passing loosely through the ends of the springs to prevent turning of said contact plates about the said bolt. 80
14. In an electric circuit controlling means of the class wherein a truck type circuit breaker 10 is located in a cell and is adapted to be wheeled out of the cell for inspection and repair purposes, the combination of a disconnect switch having two contacts adapted to be electrically connected together by means of a switch blade, one of the 15 contacts being mounted on the cell and the other contact being mounted on the circuit breaker, and a switch blade hinged to one of said contacts and having a limited amount of free side play at the hinge. 85
16. In an electric circuit controlling means of the class wherein a truck type circuit breaker 20 is located in a cell and is adapted to be wheeled out of the cell for inspection and repair purposes, the combination of a disconnect switch 25 having two contacts adapted to be electrically connected together by means of a switch blade, one of the contacts being mounted on the cell and the other contact being mounted on the circuit breaker, at least one of said contacts having a 30 limited amount of free movement whereby the switch may be closed without necessitating an accurate positioning of the circuit breaker in the cell. 90
17. In an electric circuit controlling means of 35 the class wherein a truck type circuit breaker is located in a cell and is adapted to be wheeled out of the cell for inspection and repair purposes, the combination of a disconnect switch having two contacts adapted to be electrically connected 40 together by means of a switch blade, one of the contacts being mounted on the cell and the other contact being mounted on the circuit breaker, at least one of said contacts having a limited amount 45 of free movement and adjustable in a direction toward and away from the other contact whereby the switch may be closed without necessitating an accurate positioning of the circuit breaker in the cell. 100
18. A switch comprising a pair of cantilever leaf springs, contact plates mounted on the free ends of the springs, and a switch blade pivotally bolted between the contact plates. 105
19. A switch comprising a pair of cantilever leaf springs, contact plates mounted on the free ends of the springs, and a switch blade pivotally bolted between the contact plates, said bolted mounting including a loose pin connection extending between the springs and the blade for permitting a limited lateral tilting of the blade at right angles to its plane of movement. 110
20. In combination, a terminal member, a pair of cantilever springs anchored to said member, a pair of contact plates, flexible leads connecting the contact plates with the terminal member, said contact plates being mounted between the cantilever springs by a loose mechanical connection including a bolt extending through both 115 springs and through enlarged openings in both contact plates whereby the plates are permitted a limited longitudinal and rocking motion on the bolt, and studs extending from the outer sides of the contact plates through openings in the leaf springs for guiding and limiting the extent of motion of the contact plates, said contact plates being resiliently pressed towards one another by the cantilever springs to maintain a pressure contact with such conducting member 120 as may be located between them. 125
21. In combination, a circuit breaker mounted for movement as a unit into and out of its circuit making position, an insulating bushing extending from the circuit breaker, a terminal supported by the bushing, a second terminal spaced from the breaker when the breaker is in its circuit making position, a switch blade mounted on one of said terminals and movable into and out of engagement with the other terminal while 120 the circuit breaker remains in position, said switch blade being mounted by means permitting a limited degree of side motion to permit self-alignment of the switch and the engaged terminal for different positions of the breaker. 130
